CLAIM

The ornamental design for combination bathtub insulation and cover as shown and described.

DESCRIPTION

The file of this patent contains at least one drawing/photograph executed in color. Copies of this patent with color drawing(s)/photograph(s) will be provided by the Office upon request and payment of the necessary fee.

2. Combination bathtub insulation and cover

2.1: Front

2.2: Back

2.3: Bottom, the top view being a mirror image thereof;

2.4: Right, the left view being a mirror image thereof;

2.5: Perspective

2.6: Exploded

1 Claim, 6 Drawing Sheets
